UNITED STATES PATENT OFFICE.

JARED C. BLACKMAN, OF DANBURY, CONNECTICUT, ASSIGNOR OF ONE-HALF TO ELVIRA L. STRONG, OF SAME PLACE.

MEDICAL COMPOUND.

SPECIFICATION forming part of Letters Patent No. 276,153, dated April 24, 1883.

Application filed October 30, 1882 (No specimens.)

To all whom it may concern:

Be it known that I, JARED C. BLACKMAN, a citizen of the United States, residing at Danbury, in the county of Fairfield and State of Connecticut, have invented a new and useful composition of matter for the treatment of various diseases hereinafter specified, which said composition of matter 1 compound and prepare in the form of lozenges, pills, or powder, and of which this is a specification.

My composition consists of the following ingredients, combined substantially in the proportions stated, viz: spirits of turpentine, four and one-half gills; balsam of tolu, one-fourth of an ounce; castor-oil, one-fourth of a gill; flour of gum-arabic, one-half of a pound; oil of hemlock, one-sixteenth of an ounce; tar, one-sixteenth of an ounce; balsam of fir, one-fourth of a gill; fluid extract of sarsaparilla, one-half of an ounce; salt butter, one-fourth of a pound; resin, two pounds; flour of slippery elm, three and one-half pounds; corn-starch, three-fourths of a pound; wheat-flour, three-fourths of a pound; sugar, twelve pounds; condensed milk, one pound; oil of origanum, one-fourth of an ounce. The oils, balsams, turpentine, tar, sarsaparilla, butter, gum-arabic, and resin are melted and thoroughly mingled by agitation, then cooled and incorporated with the sugar and condensed milk, then desiccated by a mixture with the flour of slippery elm, wheat-flour, and corn-starch, and molded into the form of lozenges or pills or left in the form of a powder. This medicine is intended to be taken internally by the person using it in the treatment of diseases hereinafter specified. Each lozenge contains from one to four drops of the liquid, according to the size of the lozenge, and each pill one drop of such liquid, and each grain of the powder one drop, and either of these

compounds when administered to the patient is to be administered in quantities having reference to his or her age, constitution, and nature and severity of the disease; but not more than six lozenges or four pills or four grains of the powder are to be administered at one time, and not more than three times a day to adults, and to children not more than two-thirds of the above quantity at one time and not more than three times a day, except that in either case, if the effect is not perceptible after the administration of a dose, the dose may be increased at each administration thereafter until that result shall be attained.

It is impossible to prescribe rigid rules for the administration of the medicine, but much must be left to the discretion of the person administering it.

The above composition is to be used in the treatment of all chronic diseases of the kidneys, liver, throat, lungs, stomach, bowels, and of colds, coughs, bronchial diseases, and worms in the stomach or bowels.

What I claim, and desire to secure by Letters Patent of the United States, is—

The herein-described composition of matter in substantially the proportions aforesaid, to be used in the treatment of the diseases hereinbefore specified, said composition consisting of spirits of turpentine, balsam of tolu, castor-oil, flour of gum-arabic, oil of hemlock, tar, balsam of fir, fluid extract of sarsaparilla, oil of origanum, salt butter, resin, flour of slippery elm, corn-starch, wheat-flour, sugar, and condensed milk, in substantially the proportions specified.

JARED C. BLACKMAN.
